ROOF JACK

William R. Grace, Rosemead, Calif., assignor to Trade-Wind Motorfans, Inc., Pico Rivera, Calif., a corporation of California

Filed Oct. 14, 1959, Ser. No. 846,471

6 Claims. (Cl. 98—119)

This invention relates to a device applicable to the outlet end of an exhaust duct, or the like, in a dwelling, house, or similar structure, to direct exhaust air and gases in a predetermined manner and to prevent reverse flow of air through the duct. Such devices are generally applied to the roofs of buildings to which they are related and through which the ducts extend and are commonly referred to, in the trade, as roof jacks.

It is common practice to provide blowers in dwelling houses and the like, to exhaust hot and/or polluted air from the rooms or compartments therein. In the ordinary or conventional exhaust blower installation, a suitable electric blower is mounted on or installed in the ceiling of a room, a suitable exhaust duct extends upwardly from the blower through the roof of the building to open and exhaust the air into the outside atmosphere.

It will be apparent that with a normal blower installation, such as set forth above, so long as the blower is in operation, the flow of air is upwardly and out and outside air which may be cold and/or moisture saturated is not free to flow downwardly through the duct and into the building. However, when the blower is not in operation, the above is not the case and an adverse reverse flow of air is established.

In the past, to prevent a reverse flow of air through the blower ducts opening to the exterior of buildings, so called "jacks" have been provided at the exhaust end of the ducts. The simplest form of jack consists of a simple hood-like device adapted to overlie the open end of the duct and serving to prevent moisture, such as rain, from entering the duct. Such jacks do not prevent a down-draft through the duct, especially when there is a wind out of doors which is directed towards the outlet opening or openings in the hood.

A more suitable, more or less standard form of jack construction is presently provided wherein a pivoted shutter is arranged to normally overlie the open end of the duct to prevent a down-draft therethrough, and which is adapted to swing open when the blower is in operation and by the force of the up-draft established.

Since air pressures established by the blowers in such installations are rather low, the shutters must be light and delicately balanced in order to be operated and opened by the up-drafts.

As a result of the above, that is, the light weight and delicate balance of the shutters in the ordinary jacks, when a relatively strong breeze is directed into the jacks, the shutters are lifted thereby and their effectiveness is destroyed. In other cases, where a strong wind flows past the jacks in a particular direction, a minus pressure is established which will open the shutters and create an up-draft through the ducts when such is not desired.

An object of the present invention is to provide a novel roof jack construction which will not allow a reverse flow of air through the duct to which it is related.

Another object of my invention is to provide a roof jack construction having a normally closed shutter which is adapted to be opened by the flow of exhaust air through the duct to which the jack is related and locking means related to the shutter and adapted to normally maintain the shutter closed.

An object of this invention is to provide a roof jack of the character referred to wherein the locking means is

2

released by the shutter when the shutter is urged upon by the outward flow of exhaust air.

A further object of my invention is to provide a lock means in a roof jack of the character referred to including a secondary shutter which normally overlies and closes the outlet opening in the jack and which is normally prevented from opening by the primary shutter, with the result that wind conditions about the exterior of the jack cannot cause the shutters to open and thereby permit a reverse flow of air through the jack and the duct.

The various objects and features of my invention will be fully understood from the following detailed description of a typical preferred form and application of my invention, throughout which description reference is made to the accompanying drawings, in which:

FIG. 1 is a perspective view of the roof jack provided by the present invention.

FIG. 2 is a detailed sectional view of my new construction taken substantially as indicated by line 2—2 on FIG. 1.

FIG. 3 is a sectional view of a portion of the structure shown in FIG. 2 and showing certain parts thereof in a different position.

FIG. 4 is an enlarged detailed sectional view of a portion of the structure shown in FIG. 2.

FIG. 5 is an enlarged detailed sectional view taken as indicated by line 5—5 on FIG. 3.

FIG. 6 is an enlarged detailed sectional view taken as indicated by line 6—6 on FIG. 3.

The jack construction A provided by the present invention is adapted to be related to the discharge end of an exhaust duct D, through which exhaust gases are conducted under a forced draft created by a blower, or the like.

In the preferred carrying out of the invention, the jack is adapted to be related to a duct extending through the roof R of a building and is suitably mounted on and incorporated in the roof structure. It is to be understood that while my jack is referred to as a roof jack and is, in the particular embodiment shown, most suitable for use as a roof jack, it can be advantageously employed in other than roof installations, in the form illustrated, or slightly modified and without destroying its novelty.

The jack construction A is shown as including generally, a box-like body B, mounting means C adapted to secure the body to the roof R and connect with the duct D with which the jack is related; flow control means E carried by the body and adapted to normally prevent the passage of air through the body.

The body B of the jack A is a simple sheet metal, box-like structure having vertically disposed front, side and rear walls 10, 11 and 12 and a top wall 13. The front, side and rear walls have straight bottom edges each occurring in a common plane and defining an open bottom in the body. The front wall 10 of the body is of limited vertical extent, the upper edge thereof being spaced a substantial distance below the top wall 13 and cooperating with the top wall and the side walls 11 to establish a forwardly disposed outlet opening 14 in the body.

In the particular case illustrated, the top wall 13 is in the nature of a continuation of the rear wall 12, having a curved or rounded rear portion 15 extending upwardly and forwardly from the rear wall and a straight, forwardly and slightly downwardly inclined forward portion 16.

The forward portion 16 is shown as projecting forwardly beyond the front wall 10 to establish an overhang and so that the opening outlet 14 is forwardly and downwardly disposed and is not subject to catching and admitting the entry of falling rain and the like, into the interior of the body.

The forward edges of the side walls 11 are inclined

to extend between the top edge of the front wall 10 and the forward edge of the top wall 13.

It is to be understood that the particular body configuration illustrated and described is only typical of one carrying out of the invention and that, in practice, the body can be of any other suitable design.

The mounting means E that I provide involve a substantially rectangular frame 20 having an upwardly projecting flange 21 about its inner perimeter and slidably engaged in the open bottom of the body and an outwardly projecting flange 22 about its perimeter to engage the roof R.

The flange 21 is of limited vertical extent and is fixed to the front, side and rear walls of the body as being spot welded, or the like.

The flanges 22 are of considerable lateral extent and are adapted to be cooperatively engaged in the roof structure to overlie a duct receiving opening therein, that is, it is adapted to be fixed to the roof sheathing as by means of nails and to be covered by the shingles or roofing paper (not shown).

The duct D is a simple sheet metal duct, rectangular in cross-section and corresponding in outside dimensions with the inside dimensions of the mounting means from 20. The duct extends upwardly through an opening in the roof structure and slidably enters the frame, as illustrated in the drawings.

Since the structure thus far described is only typical of conventional roof jack constructions and can vary widely in form and construction without affecting the novelty of the present invention, this specification will not be burdened with further unnecessary details thereof.

The flow control means E that I provide is adapted to normally prevent the flow of air through the body and is such that it will open and allow for the free flow of air through the body, only when air is introduced into the body, under slight pressure, through the duct D.

The means E is shown as including a partition 30 in the body, a primary shutter 31 adapted to normally overlie and close an aperture 32 in the partition, a secondary shutter 33 adapted to normally extend across and close the outlet opening 14 in the body and a trigger 34 carried by the secondary shutter to engage the primary shutter, whereby the said secondary shutter is opened by the primary shutter when the primary shutter is urged open by the introduction of air under pressure into the body, through the duct.

The partition 30 is a simple, flat, sheet metal plate arranged within the body to extend rearwardly and upwardly from the upper edge of the front wall 10 to the rear portion 15 of the top wall 13. The sides of the partition are provided with flanges 35 to abut the side walls 11 of the body to which they are fixed as by spot welding, or the like.

The aperture or opening 32 in the partition is a simple rectangular opening and is defined by an upwardly turned, flange-like lip 36 formed in the partitions.

The primary shutter 31 is a simple, rectangular, flat, sheet metal plate arranged within the body B to occur above the partition 30 and to normally engage and seat on the lip 36 about and defining the aperture 32 to close the same.

The shutter 31 is provided along its side edges with reinforcing flanges 37.

The forward edge of the shutter 31 is formed to establish a flange-like stop 38 to engage the secondary shutter 33, as will hereinafter be described.

The rear edge of the shutter 31 is formed, as by rolling, to establish a transversely extending opening in which a pivot rod 39 is engaged.

The pivot rod 39 projects laterally from the opposite sides of the shutter and is rotatably engaged and supported in suitable bearings 40 carried by the side walls 11 of the body.

The bearings 40 can be of any suitable design without in any way affecting the invention.

In practice and as disclosed, a suitable gasket 41 is provided on the underside of the shutter 31 to occur between the shutter and the flange 36 on the portion and to establish a seal therebetween when the shutter is closed.

With the structure set forth above, it will be apparent that the shutter 31, by the force of gravity, normally rests upon the flange 36 to overlie and close the aperture 32. It will be further apparent that when air is introduced under pressure into the lower part of the body, through the duct D, as by means of a blower (not shown), the shutter 31 is free to be raised thereby, about its pivotal axis, and so as to allow the said air to flow through the aperture and then outwardly through the outlet opening 14 of the hood.

The secondary shutter 33 is a simple, flat, rectangular, sheet metal part arranged within the body to occur at or just inward of the outlet opening 14 therein to normally extend across and close the opening. The shutter 33 has a straight top edge 42 which normally occurs adjacent the under side of the top wall 13 of the body, side edges 43 which occur adjacent the side walls 11 of the body and a straight bottom edge 44 which normally occurs adjacent the partition 30, forward of the aperture 32 therein and adjacent the stop 38 along the forward edge of the primary shutter 31.

The shutter 33 is provided with a pair of laterally projecting pivot pins 45 at its side, which pins are engaged in suitable bearings 46 carried by the side walls 11 of the body. The pins 45 are positioned intermediate the top and bottom edges of the shutter and the bearings intermediate the top and bottom edges of the side walls to cooperatively receive the pins and so that the shutter is mounted to pivot about its center of gravity.

In practice, a suitable upwardly projecting stop boss 50 is provided on the partition 30 to occur forward of the shutter 33 and prevent the lower portion of the shutter 33 from swinging forwardly and out of proper position.

In practice, if desired, a suitable stop means 51 can be provided at the top of the hood to limit excessive rearward swinging of the upper portion of the shutter 33. The means 51 can be provided to supplement the boss 50, or can replace the boss, as desired or as circumstances require.

When the shutters 31 and 33 are in their normal closed positions, as illustrated in FIG. 2 of the drawings, it will be apparent that the stop flange 38 along the forward edge of the shutter 31 opposes the rear-bottom edge of the shutter 33, with the results that the shutter 31 effectively stops or prevents rearward shifting of the bottom edge of the shutter 33 and resulting opening thereof. However, when the shutter 31 is pivoted to its open position, the flange stop 38 therein is shifted from position behind the lower or bottom edge of the shutter 33 and the shutter 33 is free to swing to its open position.

It will be apparent that in order for the jack construction that I provide to function properly, the shutters 31 and 33 must both open at substantially the same time, since if the shutter 31 should open and shutter 33 remain closed, a fluctuating static pressure would be established in the body and the shutter 31 would rapidly open and close.

In order to assure the simultaneous opening of the shutters 31 and 33, I provide the trigger 34, referred to above, on the shutter 33. The trigger 34 is a simple L-shaped member having one leg fixed to the rear side of the shutter 33, substantially centrally thereof, to project rearwardly therefrom and its other leg depending from the rearmost end of the first leg to terminate adjacent the top surface of the shutter 31 at a point spaced rearward of the forward edge thereof.

It will be apparent that when the primary shutter 31

is urged upwardly and open, it engages the trigger 34, which acts as a lever to open the secondary shutter 33.

In practice and as illustrated, the trigger is proportioned so that when the shutter 33 is in its fully open position, that is, when the shutter occurs in a plane substantially normal to the plane of the outlet opening 14 in the body, it engages the top wall 13 of the body and serves as a stop to prevent excessive turning of the shutter, as clearly illustrated in FIG. 3 of the drawings.

When the flow of air through the body is shut off, the primary shutter 31 is free to drop. As it drops, it engages the shutter 33 and urges it back to its normal position.

If circumstances require, the shutter 33 can be provided with suitable balance weights to assure easy operation. In the case illustrated, I have shown the lower edge of the shutter 33 suitably rolled over to provide additional stock and resulting weight for the purpose of balancing the shutter and have shown additional balance weights 60 within the said rolled edge.

With the construction set forth above, it will be apparent that I have invented a novel roof jack construction which will allow for the free outward flow of exhaust air and/or gases, and such that it will stop and prevent a reverse flow of air therethrough as might occur in a conventional roof jack construction when subjected to strong winds, or the like.

Having described only a typical preferred form and application of my invention, I do not wish to be limited or restricted to the specific details herein set forth, but wish to reserve to myself any modifications or variations that may appear to those skilled in the art and fall within the scope of the following claims.

Having described my invention, I claim:

1. A roof jack of the character referred to including, a body having an inlet opening to communicate with an exhaust duct, and a forward open side defining an outlet opening, an apertured partition in the body above the inlet opening, a primary shutter having front and rear edges, said rear edge being pivotally connected to the body on an axis transverse the body and adjacent the rear edge of the aperture in the partition, said shutter normally overlying the aperture in the partition, a secondary shutter with upper and lower edges and parallel sides, means at the sides of the secondary shutter intermediate the top and bottom edges thereof pivotally connecting the shutter to the body to normally extend across and close the outlet opening, said lower edge of the primary shutter occurring adjacent the forward edge of the secondary shutter when the shutters are in their normal closed position and serving to normally maintain the secondary shutter closed.

2. A roof jack of the character referred to including, a body having an inlet opening to communicate with an exhaust duct, and a forward open side defining an outlet opening, an apertured partition in the body above the inlet opening, a primary shutter having front and rear edges, said rear edge being pivotally connected to the body on an axis transverse the body and adjacent the rear edge of the aperture in the partition, said shutter normally overlying the aperture in the partition, a secondary shutter with upper and lower edges and parallel sides, means at the sides of the secondary shutter intermediate the top and bottom edges thereof pivotally connecting the shutter to the body to normally extend across and close the outlet opening, said front edge of the primary shutter occurring adjacent the lower edge of the secondary shutter when the shutters are in their normal closed position and serving to normally maintain the secondary shutter closed, a trigger on the secondary shutter projecting rearwardly and downwardly from the pivotal axis thereof and engaging the primary shutter whereby said secondary shutter is pivoted open by the primary shutter when the primary shutter is pivoted open.

3. A roof jack of the character referred to including,

a box-like body having an inlet opening in its bottom side and an outlet opening in its forward side, a substantially horizontally disposed, apertured partition in the body overlying the inlet opening, a substantially horizontally disposed primary shutter arranged within the body to normally overlie and close the aperture in the partition, means pivotally securing the shutter to the partition adjacent the rear of the aperture therein, said shutter having a forward edge extending transversely of the outlet opening, a substantially vertically disposed secondary shutter having top, bottom and side edges arranged in the body to normally extend across and close the outlet opening, pivot means at the side of the shutter between the top and bottom edges therein and engaging the body,

10 the lower edge of the secondary shutter normally occurring adjacent and stopped by the forward edge of the primary shutter, a trigger fixed to and projecting rearwardly and downwardly from the center of the secondary shutter and engaged by the primary shutter, said primary shutter 15 adapted to be pivoted upwardly to an open position by the flow of air into the body through the inlet opening and away from the secondary shutter whereby the secondary shutter is free to pivot to a substantially horizontally disposed, open position, said primary shutter 20 engaging the trigger upon upward movement to pivot open 25 said secondary shutter.

4. A roof jack of the character referred to including, a box-like body having an inlet opening in its bottom side and an outlet opening in its forward side, a substantially horizontally disposed, apertured partition in the body overlying the inlet opening, a primary shutter having front and rear edges arranged within the body to normally overlie and close the aperture in the partition, means pivotally connecting the rear edge of the shutter in the 30 construction with its front edge extending transversely of the outlet opening, a substantially vertically disposed secondary shutter arranged in the body to normally extend across and close the outlet opening and pivotally supported in the body at the sides thereof intermediate the top and bottom thereof and having a lower edge which 35 normally occurs adjacent and is stopped by the forward edge of the primary shutter, a trigger fixed to and projecting rearwardly and downwardly from the pivotal axis of the secondary shutter and engaged by the primary, 40 said primary shutter being pivoted to an open position by upward flow of air into the body through the inlet opening and away from the secondary shutter whereby the secondary shutter is free to pivot to a substantially horizontally disposed, open position, said primary shutter 45 engaging the trigger upon upward movement to pivot and 50 open said secondary shutter.

5. A roof jack of the character referred to including, a box-like body having an inlet opening in its bottom side and an outlet opening in its forward side, a substantially horizontally disposed, apertured partition in the body overlying the inlet opening, a substantially horizontally disposed primary shutter arranged within the body to normally overlie and close the aperture in the partition, means pivotally connecting the shutter in the construction 55 at its rearmost end, said shutter having a forward edge extending transversely of the outlet opening, a substantially vertically disposed secondary shutter arranged in the body to normally extend across and close the outlet opening pivot means at the sides of the secondary shutter intermediate the top and bottom thereof and engaging the sides 60 of the body, said secondary shutter having a lower edge which normally occurs adjacent and is stopped by the forward edge of the primary shutter, a trigger fixed to and projecting rearwardly and downwardly from the center of the secondary shutter the primary shutter 65 adapted to be pivoted upwardly and rearwardly away from the secondary shutter to an open position by the flow of air into the body through the inlet opening whereby the secondary shutter is free to pivot to a substantially 70 horizontally disposed, open position, said primary shutter 75

engaging the trigger upon upward movement to pivot and open said secondary shutter, said trigger engaging the top of the body when the secondary shutter is open to prevent excessive pivoting of the secondary shutter.

6. A roof jack of the character referred to including, a box-like body having an inlet opening in its bottom side and an outlet opening in its forward side, a substantially horizontally disposed, apertured partition in the body overlying the inlet opening, a primary shutter having front and rear edges arranged within the body to normally overlie and close the aperture in the partition, and means pivotally connecting the rear edge of the shutter in the body, the forward edge extending transversely of the outlet opening, a substantially vertically disposed secondary shutter arranged in the body to normally extend across and close the outlet opening and means pivotally connecting the secondary shutter in the body on an axis intermediate and parallel with the top and bottom edges of the said shutter the bottom edge of the secondary shutter normally occurring adjacent and stopped by the forward edge of the primary shutter, a trigger fixed to

and projecting rearwardly from the central portion of the secondary shutter, said primary shutter adapted to be pivoted upwardly and rearwardly to an open position and away from the secondary shutter by the flow of air into the body through the inlet opening whereby the secondary shutter is free to pivot to a substantially horizontally disposed, open position, said primary shutter engaging the trigger upon upward movement to pivot and open said secondary shutter, said partition having an upwardly turned sealing lip about the perimeter of the aperture therein and said primary shutter having a sealing member fixed thereto to engage the lip when the shutter is in its normal closed position.
